UNITED STATES PATENT OFFICE.

EDWIN J. ARMSTRONG, OF ERIE, PENNSYLVANIA, ASSIGNOR, BY DIRECT AND MESNE ASSIGNMENTS, TO ERIE STEAM SHOVEL COMPANY, OF ERIE, PENNSYLVANIA, A CORPORATION OF PENNSYLVANIA.

HOISTING APPARATUS.

Application filed February 13, 1923. Serial No. 618,817.

To all whom it may concern:

Be it known that I, EDWIN J. ARMSTRONG, a citizen of the United States, residing at Erie, in the county of Erie and State of Pennsylvania, have invented new and useful Improvements in Hoisting Apparatus, of which the following is a specification.

This invention is designed to control the leading device of a cable operating in connection with an adjustable boom so that the cable may be properly guided to the drum with different adjustments of the boom and at a distance from the drum to facilitate the winding of the cable.

15 The invention is illustrated in the accompanying drawings as follows:—

Fig. 1 shows a drag line apparatus provided with the structure of the invention.

Fig. 2 a plan view of the parts at the base 20 of the boom including the leading device.

Fig. 3 a side elevation of the same parts on the line 3—3 in Fig. 2.

Fig. 4 a side elevation of the base of the boom showing various adjustments of the boom and the relation of the leading device to the drum.

1 marks a truck, 2 a swinging platform mounted on the truck, 3 a boom pivotally mounted at 4 on the swinging platform, 5 cables running to the upper end of the boom and secured at 6 to the swinging platform for adjusting the inclination of the boom, 7 a drag line bucket, 8 a hoisting cable for the drag line bucket, 9 a sheave at the top of 35 the boom for the cable 8, 10 a drum which operates the cable, 11 a drag line, and 12 a drum on which the drag line is wound. These parts are, or may be, of ordinary construction.

40 It is common to provide the drag line with a guiding or leading means arranged above the pivot of the boom. This makes the inclination from this leading device to the drum so abrupt as to interfere with the free

45 winding of the cable on the drum. It is desirable, therefore, to mount the leading device in advance of the boom and the only convenient mounting at this point is on the boom itself. Where this is done the changing 50 of the inclination of the boom varies the relation of the leading device to the tangent on the drum. The present invention provides a means by which this device may be

adjusted to maintain the proper relation between the drum and the device.

Horizontal lead sheaves 13 are mounted in a sheave carrier 14. The sheave carrier 14 has the trunnions 15 by means of which it is pivotally mounted in the sheave carrier mounting 16. Vertical sheaves 17 are also mounted in the sheave carrier 14 in advance of the sheaves 13. It will readily be seen that by the swinging of the carrier the sheave 17 may follow the cable in the different positions to which the drag bucket 60 may be moved, or the different relations which may be established by the swinging of the platform. The horizontal sheaves take the thrust of the cable incident to the variation in direction brought about by the 70 winding of the cable on the drum and also the variation in the direction of the drag bucket in the usual manner. The mounting 16 is connected by a pivot pin 18 with a bracket 19 so that the device as a whole is 75 carried by the boom 3.

An adjusting bar 20 is pivotally connected at 21 with the carrier mounting 16, the pivotal point 21 being off-set from the pivot 18 and the opposite end of the bar 20 is pivotally secured at 22 on a bracket 23 secured to the swinging frame. The pivot 22 is off-set as it will be seen from the pivot of the boom 3. The off-set distances between the pivot 18 and pivot 21 and the pivot 4 and 85 pivot 22 are so proportioned relatively to each other as to govern the swinging mounting of the mounting 16 as the boom is lowered or raised to maintain its relation to a tangent running to the drum so that the 90 cable leading from the drum to the sheave 13 is maintained in proper relation to these sheaves with the various adjustments of the boom as clearly illustrated in Fig. 4 wherein various adjustments of the boom are 95 shown.

What I claim as new is:—

1. In a hoisting apparatus, the combination of a boom adjustable as to inclination; a hoisting drum; a cable winding on the 100 drum; a cable leading device on the boom; and a mounting for said device adjustable with the adjustment of the boom maintaining the alignment of the device with the drum.

2. In a hoisting apparatus, the combina-

tion of a boom adjustable as to inclination; a hoisting drum; a cable winding on the drum; a cable leading device on the boom comprising sheaves having their grooves tangential to the drum; and a mounting for said device adjustable with the adjustment of the boom maintaining the tangential relation of the sheaves with the drum.

3. In a hoisting apparatus, the combination of a boom adjustable as to inclination; a hoisting drum; a cable winding on the drum; a cable leading device comprising a vertically pivoted sheave carrier; a horizontally pivoted carrier mounting for the sheave carrier; and means adjusting the mounting as the boom is adjusted to maintain the sheave carrier in alignment with the drum.

4. In a hoisting apparatus, the combination of a boom adjustable as to inclination; a hoisting drum; a cable winding on the drum; a cable leading device comprising a vertically pivoted sheave carrier; a horizontally pivoted carrier mounting for the sheave carrier; and means for adjusting the mounting as the boom is adjusted to maintain the sheave carrier in alignment with the drum, said means comprising a bar connect-

ed to the sheave carrier mounting off-set from the pivot of said mounting, the opposite end of the bar being mounted off-set from the axis of the boom.

5. In a hoisting apparatus, the combination of a boom; a platform; a pivotal mounting for the boom on the platform; a drum mounted on the platform; a cable winding on the drum; a leading device mounted on the boom, said leading device comprising a sheave carrier having horizontal and vertical sheaves therein, the horizontal sheaves having their grooves tangential to the drum; a carrier mounting for the sheave carrier pivoted on the drum with a horizontal pivot; and a bar pivotally connected to the mounting and pivotally connected to the platform, said pivotal connections of the bar being off-set from the pivotal connection of the mounting and the pivotal connection of the boom with the platform, the off-set distances being proportioned to maintain the tangential relation between the sheaves and the drum as the boom is adjusted.

In testimony whereof I have hereunto set my hand.

EDWIN J. ARMSTRONG.
